Primary Examiner — Sheryl Lane*Assistant Examiner* — Leisha N Price(74) *Attorney, Agent, or Firm* — Quickpatents, LLC; Kevin Prince(57) **CLAIM**

The ornamental design for a lifting eye, as shown and described.

DESCRIPTION

FIG. 1 is a top perspective view of a lifting eye, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a cross-sectional view thereof, taken along line 8--8 of FIG. 4; and,

FIG. 9 is a cross-sectional view thereof, taken along line 9--9 of FIG. 3.
